UNITED STATES PATENT OFFICE

143,256

DESIGN FOR A VEHICLE BODY

George W. Walker, Detroit, Mich., assignor to
The Baker-Raulang Company, Cleveland, Ohio, a corporation of Ohio

Application June 30, 1945, Serial No. 120,432

Term of patent 7 years

(Cl. D14—3)

To all whom it may concern:

Be it known that I, George W. Walker, a citizen of the United States, residing at Detroit, in the county of Wayne and State of Michigan, have invented a new, original, and ornamental Design for Vehicle Body, of which the following is a specification, reference being had to the accompanying drawing, forming part thereof.

Fig. 1 is a perspective view of a vehicle body showing my new design;

Fig. 2 is a side elevational view;
Fig. 3 is a rear elevational view; and
Fig. 4 is a top plan view.

The side of the vehicle body opposite to that shown in Figs. 1 and 2, is the same as illustrated.

I claim:

The ornamental design for a vehicle body, as shown and described.

GEORGE W. WALKER,
